UNITED STATES PATENT OFFICE.

WILLIAM H. TILLSON, OF QUINCY, ILLINOIS.

OVERSHOE ATTACHMENT.

1,308,206.

Specification of Letters Patent.

Patented July 1, 1919.

Application filed March 12, 1919. Serial No. 282,144.

To all whom it may concern:

Be it known that I, WILLIAM H. TILLSON, a citizen of the United States, residing at Quincy, in the county of Adams and State 5 of Illinois, have invented a new and useful Overshoe Attachment, of which the following is a specification.

It is the object of this invention to provide an overshoe attachment including a 10 bail which can be made cheaply, without the use of a die, in the formation of the arms of the bail. Within the scope of what is claimed, a mechanic may work changes without departing from the spirit of the 15 invention.

In the drawings:—Figure 1 is a perspective; Fig. 2 is a section on the line 2—2 of Fig. 1; Fig. 3 is a plan showing one end of the bail-forming strip before the same is 20 bent to form the arms; Fig. 4 is a plan showing the strip after it has been bent.

The numeral 1 denotes a bail made out of a ribbon-like metal strip 2 folded upon itself at 3 along diagonal lines 4 adjacent to its 25 ends to form arms 5 disposed approximately at right angles to the body portion 6 of the bail, and to form a double-thick reinforcement 7 where each arm merges into the body of the bail. The bail is provided with a 30 tongue 8 facilitating the manipulation of the bail.

The invention includes a carrier 9 in the form of a U-shaped metal member having notches 10 in its upper edge near its ends, 35 there being clips 11 on the upper edge of the carrier, on both sides of each notch 10. Any suitable means may be provided for pivoting the arms 5 of the bail 1 to the carrier 9. The arms 5 extend outwardly

through the notches 10 and may be supplied 40 with openings 14 received on the outwardly extended U-shaped parts 12 of wire retainers including inwardly extended U-shaped parts 15, terminating in outwardly extending prongs 16 which are bendable, the retainers being mounted in the end portions 45 of the carrier 9.

The carrier 9 is placed inside an overshoe and is held thereon by the clips 11 and the prongs 16, the latter parts being extended 50 outwardly through the overshoe and being clenched thereon. When the bail 1 is swung upwardly into the position shown in Fig. 1, the overshoe will be held on the foot of the wearer. When the bail 1 is not in use, the 55 same may be swung downwardly inside of the carrier 9.

Especial attention is directed to the way in which the arms 5 of the bail are formed by bending the strip 3 at 4. Not only does 60 this construction render the use of a die unnecessary, but, at the same time, an unusually strong construction is afforded.

I claim:

An overshoe attachment comprising a U- 65 shaped bail fashioned from a ribbon-like strip of metal folded upon itself along diagonal lines adjacent to its ends to form arms disposed approximately at right angles to the body portion of the bail, and to form 70 double-thick reinforcements at the places where the arms merge into the body portion of the bail; a carrier; and means for pivoting the arms to the carrier.

In testimony that I claim the foregoing 75 as my own, I have hereto affixed my signature.

WILLIAM H. TILLSON.
